BUTADIENE PRODUCTION BY THE
PYROLYSIS OF DIISOPROPYLEdmond L. d'Ouville and Alex G. Oblad, Chicago,
Ill., assignors to Standard Oil Company, Chi-
cago, Ill., a corporation of IndianaNo Drawing. Application July 13, 1942,
Serial No. 450,799

3 Claims. (Cl. 260—630)

This invention relates to the production of butadiene from hydrocarbon charging stocks and it pertains more particularly to a new and improved method of butadiene production involving the pyrolysis or demethanation of diisopropyl (2,3-dimethylbutane).

Butadiene has been prepared in small amounts by pyrolysis of various hydrocarbons but always with low yields and large gas production. The most outstanding results heretofore obtained by the pyrolysis of saturated hydrocarbons required the use of cyclohexane as a charging stock. An object of our invention is to provide a method of producing butadiene from hydrocarbon charging stocks which will produce larger butadiene yields than any heretofore obtainable. A further object is to minimize the production of other C₄ hydrocarbons and to minimize polymerization and secondary reactions in the diisopropyl pyrolysis step. A further object is to provide a process which will minimize the problem of recovering butadiene from conversion products. Other objects will be apparent as the detailed description of the invention proceeds.

We have discovered that large yields of butadiene can be obtained by the thermal pyrolysis of diisopropyl. Diisopropyl does not occur in any significant amounts in crude petroleum or in the ordinary distillation products thereof, crude light naphthas containing only about .01 to 2%. It may, however, be synthetically produced by the alkylation of isobutane with ethylene in the presence of an aluminum halide catalyst. It may also be obtained by various methods of chemical synthesis. We prefer, however, to employ the isobutane-ethylene alkylation process for the production of the diisopropyl because this process has been found to be commercially practical for producing large yields of the diisopropyl at relatively low cost.

Diisopropyl is unique among the hydrocarbons now available or likely to become commercially available for butadiene manufacture in that the main primary C₄ product which can result from its pyrolysis is the much desired butadiene. Actual pyrolysis of this hydrocarbon has shown, however, that unless conditions are carefully controlled, there will be considerable amounts of isobutylene and other products formed because of secondary reactions. By using carefully controlled conditions, however, we can obtain large yields of butadiene and a minimum of undesirable products.

We may obtain diisopropyl from any source whatsoever but we preferably obtain it by the iso-

butane-ethylene alkylation reaction with an aluminum chloride catalyst. The charging stock need not, of course, be pure diisopropyl but it should be rich in diisopropyl, i. e., should contain at least 20 to 50% of it and preferably should contain more of this than any other hydrocarbon in its composition, the higher the diisopropyl content, the better for our purpose. The charging stock is subjected to pyrolysis at a temperature of 5 to 10 the order of about 1200 to 1650° F., preferably within the range of 1350 to 1550° F., with a reaction time of the order of .01 to 10 seconds, ordinarily below 5 seconds and preferably in the general vicinity of 1 second or less, and at a pressure of the order of .1 to 10 atmospheres, preferably as low as is commercially feasible. An inert diluent such as steam, carbon dioxide, nitrogen, etc., may be employed for repressing undesirable secondary reactions and a quick cooling or 15 quenching is likewise preferably employed for the same purpose. The total product may be injected into water, or it may be absorbed in a naphtha or other hydrocarbon oil having an initial boiling point substantially above the boiling point 20 of diisopropyl. In the latter case the rich absorber oil solution can be depropanized after which a cut rich in butadiene may be recovered therefrom by simple distillation and unconverted diisopropyl can be recycled to the process. The 25 butadiene can be further purified if necessary by conventional methods.

For obtaining the diisopropyl, isobutane may be alkylated with ethylene at a temperature within the approximate range of 0 to 250° F., preferably within the more limited range of about 50 to 150° F., for example about 100 to 125° F. The pressure for such alkylation may be within the approximate range of atmospheric to 1000 pounds per square inch but preferably is in the more limited range of about 50 to 150 pounds per square 30 inch and should be sufficient to maintain the reactants in liquid form. The catalyst for the alkylation is preferably an aluminum chloride-hydrocarbon complex containing within the approximate range of 23 to 32%, for example 28% of bound hydrocarbon. This complex is prepared by the interaction of an aluminum halide and a hydrocarbon which is a hydrogen halide preferably paraffinic (iso-paraffinic), naphthenic or olefinic and the resulting complex will have a heat of hydrolysis within the approximate range of 60 to 75 large calories per gram atom of active aluminum in the case of aluminum chlorides or in the case of aluminum bromide complex between 67 or 82 large calories per gram atom of

active aluminum. As a specific example of diisopropyl preparation about four parts by weight of isobutane are alkylated with about one part by weight of ethylene at a temperature of about 105° F. under a pressure of about 100 pounds per square inch for a period of about five hours by intimately contacting the reactants with an aluminum chloride-hydrocarbon complex having a heat of hydrolysis of about 67 large calories per gram atom of active aluminum. The complex is used in quantities of at least 10% by volume in batch processes and may be used to the extent of 100 or 200% or more. The stabilized liquid product from this reaction contains about 70% of C₆ hydrocarbons of which about 88% is diisopropyl and 12% is 2-methyl pentane. It is preferable to maintain an excess of isobutane in this alkylation reaction since an excess of the ethylene would lead to the formation of polymer products. The mol ratio of isobutane to ethylene should be greater than 1:1 and should preferably be at least about 3:1 to 4:1 or higher.

While we prefer to employ the aluminum chloride-hydrocarbon complex as a catalyst it should be understood that we may simply employ aluminum chloride or aluminum bromide per se and still obtain substantial yields of C₆ hydrocarbons containing substantial amounts of diisopropyl. Where pure aluminum chloride is employed as a catalyst under the conditions referred to in the above example, the stabilized liquid product yield is lower, the C₆ hydrocarbon content of the liquid products is substantially lower (only about 45% instead of about 70%) and the diisopropyl content of the C₆ fraction is likewise substantially lower (about 45 volume percent as compared to 88 volume percent). Nevertheless, diisopropyl could be produced by aluminum chloride per se or by an inorganic aluminum chloride complex such as sodium aluminum chloride, lithium aluminum chloride, etc. Generally speaking, any Friedel-Crafts type catalyst may be used, particularly aluminum halide catalysts which include pure aluminum halides as well as catalyst complexes. When pure aluminum chloride is employed it is desirable to use lower temperatures or to employ an inert solvent or diluent for suppressing undesirable side reactions. An activator such as a hydrogen halide exemplified by hydrogen chloride, hydrogen bromide, etc. may be employed particularly in a continuous alkylation process where catalyst or aluminum chloride is continuously added to the reactor but activators are not as essential in this alkylation process as they are in the aluminum chloride isomerization process. When activators are used they should generally be in concentrations of less than about 4% based on aluminum chloride. The presence of hydrogen apparently slows the rate of the alkylation reaction and therefore the alkylation is usually effected in the absence of added hydrogen.

The isobutane may be a component of a C₄ hydrocarbon stream, i. e., may be associated with normal butane and butenes. Similarly the ethylene may be associated with ethane or other hydrocarbons. If propylene and butenes are present in the alkylation reaction the resulting alkylate will be C₇ and C₈ hydrocarbons respectively which may be easily separated from C₆ hydrocarbons (diisopropyl) by simple fractional distillation. The alkylation process may, of course, be batchwise, multi-stage or continuous.

For converting the diisopropyl into butadiene we prefer a charging stock containing as high a percent of diisopropyl as is commercially feasible

although it is not necessary of course that the diisopropyl be absolutely pure. A C₆ fraction from an isobutane-ethylene alkylation containing from about 50% to 90% diisopropyl is a preferred charging stock. Crude petroleum and the distillation products thereof contain too small amounts of diisopropyl to be of any significance in our process. The crude petroleum fractions, even close cut fractions, heretofore subjected to pyrolysis at high temperatures yielded only about 2% of butadiene and gave a dry gas production of about ten to twenty times the butadiene production. In our process the dry gas production is minimized and high yields of butadiene are produced.

The diisopropyl charging stock (for example the C₆ fraction from isobutane-ethylene alkylation) is rapidly heated to a temperature of the order of 1200 to 1650° F., preferably to about 1350 to 1500° F. and the diisopropyl is maintained at this high temperature for a very short period of time, preferably in the presence of an inert diluent in order to avoid polymerization or other secondary reactions. The duration of the high temperature pyrolysis step, or the so-called "time of contact," should be within the approximate range of .01 to 10 seconds and is preferably of the order of 1 second or less. A diluent such as steam, carbon dioxide, nitrogen, or the like, may be employed in large amounts, for example about 80% based on charging stock. In addition to employing the short time of contact and the diluent for avoiding secondary reactions we employ quick cooling or quenching. Thus the hot reaction products may be injected into water or oil or other quenching liquid for obtaining substantially instantaneous cooling in order to further safeguard against secondary or other side reactions. Relatively low pressures should be employed generally within the range of about .1 to 10 atmospheres, for example, approximately atmospheric temperature.

It is essential in the diisopropyl pyrolysis step to avoid polymerization of the ethylene or primary pyrolysis products (including the butadiene itself), hence the reaction is preferably carried out in the absence of conventional cracking catalysts since such catalysts have a polymerizing action, particularly under the conditions hereinabove set forth. We do not, however, necessarily exclude the use of catalysts such as calcium aluminate or contact materials since contact materials may serve an important function in obtaining effective heat transfer for the thermal pyrolysis and may, in fact, prevent to a certain extent undesirable isomerization and polymerization while promoting the demethanation of diisopropyl. Examples of contact materials which may be employed include Monel metal, steel filings, carbon rings, carborundum, but generally speaking our process does not require the presence of such contacting agents.

When diisopropyl is subjected to pyrolysis at temperatures substantially below about 1200° F. the butadiene production is too low to be of commercial significance. However, at a temperature of about 1400° F. and with a short contact time we have produced about half again as much butadiene as was produced by the pyrolysis of cyclohexane under the same operating conditions. A preferred example of our process is substantially as follows: a charging stock consisting essentially of diisopropyl is vaporized and admixed with about 80% by weight of steam. This mixture is then passed through a high-temperature-alloy tube heated by the usual means, for exam-

ple, radiant energy from glow bars, incandescence wires, high frequency induction or by contact with hot gases such as the products of combustion of waste refinery gases, at such a rate that the diisopropyl vapors will be subjected to a temperature of about 1350 to 1500° F. for a period of about one-half second to one second. The products are immediately injected into a body of water or other quenching liquid to avoid secondary or side reactions. The resulting products may be fractionated by conventional means and it will be found that large yields of butadiene may be obtained along with considerable amounts of methane and smaller amounts of other hydrocarbon gases.

While we have described in detail a preferred embodiment of our invention and preferred operating conditions therefor, it should be understood that our invention is not limited to the specific details hereinabove set forth since various modifications and alternative procedures and conditions will be apparent from the above description to those skilled in the art.

We claim:

1. The method of producing butadiene which comprises heating a charging stock containing more diisopropyl than any other hydrocarbon in

its composition and containing at least 20% of diisopropyl to a temperature within the approximate range of 1200 to 1650° F., subjecting said charging stock to said temperature for a period of time within the approximate range of .01 to 10 seconds, maintaining the charging stock at a pressure within the approximate range of .1 to 10 atmospheres during the heating step, immediately quenching the products leaving the heating step and fractionating the products to recover butadiene therefrom.

2. The method of claim 1 wherein the duration of the high temperature treating step is in the general vicinity of one second.

3. The method of producing butadiene which comprises subjecting a charging stock containing at least 50% by weight of diisopropyl to a temperature in the approximate range of 1350 to 1500° F. in the presence of a large amount of diluent gas for a time of contact in the general vicinity of one second and at a low pressure for demethanating the diisopropyl and forming butadiene as primary conversion product and immediately quenching the conversion products to prevent polymerization and secondary reactions.
